UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

ROTARY WEB-PRINTING PRESS.

1,240,015.

Specification of Letters Patent. Patented Sept. 11, 1917.

Application filed May 23, 1916. Serial No. 99,321.

To all whom it may concern:

Be it known that I, HENRY F. BECHMAN, a citizen of the United States, residing at Battle Creek, in the county of Calhoun and 5 State of Michigan, have invented certain new and useful Improvements in Rotary Web-Printing Presses; and I hereby declare that the following is a full, clear, and exact description thereof, reference being had to 10 the accompanying drawings, which form part of this specification.

This invention relates to rotary web printing presses, its object being to provide a web printing press of large capacity; capable of 15 producing a great variety of product according to the size of the paper desired; which can be used for printing in one color or in multi-color; and in which the several webs after being printed may, if desired, all be assembled at one folder or assembled at different folders, according to the size and number of the papers which it is desired to print. Also to make such press compact, and yet have all the parts thereof readily accessible.

25 The invention is particularly adapted for newspaper work and the press is especially designed for using tubular single-page-stereotype plates, such as shown in my Reissue Patent No. 13,129 of July 12, 1910.

30 The invention, furthermore, is an improvement upon the type of presses shown in my application for patent on rotary cylinder printing press, filed September 12, 1912, Serial No. 719,967.

35 I will explain the invention more fully with reference to the accompanying drawings and summarize in the claims the essential novel features, combinations, and arrangement of parts for which protection 40 is desired.

In said drawings:

Figure 1 is a diagrammatical side elevation of a novel printing press, embodying the invention, and for clearness of illustration showing in dotted lines the folding devices and means for directing the printed webs to the folders which are located at the side of the press.

Fig. 2 is a diagrammatic top plan view 50 of such press, showing the relative positions of the folding and printing mechanisms and web deflectors and omitting the inking mechanisms and guide rollers.

Fig. 3 is a view similar to Fig. 1 showing how the press may be threaded for 55 multi-color work.

Fig. 4 is a diagrammatic elevation of the press looking at the left hand end of the press as shown in Fig. 2.

Fig. 5 is a similar view looking at the 60 right hand end of the press as shown in Fig. 2.

As shown, the press has a central large impression cylinder 1, with which coöperate six plate cylinders 2, 3, 4, 5, 6 and 7, each 65 of which plate cylinders is provided with suitable inking mechanisms, indicated at I², I³, I⁴, I⁵, I⁶ and I⁷, each inking mechanism comprising form rollers, distributing and vibrating rollers, and an ink fountain, as 70 will be readily understood by press builders.

In the example shown each plate cylinder is short and adapted to carry but two tubular plates, such as described in my patent aforesaid. The impression cylinder 1 is four 75 plates long and therefore the two upper plate cylinders 5 and 6 and the two lower plate cylinders 2 and 3 are preferably arranged adjacent one end of the impression cylinder 1; while the plate cylinders 4 and 7 are arranged adjacent the other end of the cylinder 1, as indicated in Fig. 2, to enable a four page wide web to be printed as hereinafter explained. The plate cylinders are 80 suitably journaled and supported in the frame of the press, not shown, so that tubular plates may be slipped endwise onto and over outer ends of the plate cylinders, from 85 the sides of the press, as explained in my aforesaid patent and application. 90

My object in using short plate cylinders is to prevent springing thereof when operating at high speed. It will be understood, however, that while I prefer, and the press is particularly designed, to use small plate 95 cylinders carrying tubular plates, the invention is not to be limited to such tubular plates, unless specifically mentioned in the claims, as it would be practical to utilize substantial and important parts and features of the invention and employ plate cylinders carrying ordinary semi-cylindric stereotype plates. 100

At opposite sides of the central group of printing mechanisms described, are arranged two groups of printing mechanisms;

each group, in the example shown, comprising three printing couples arranged in superposed planes. Thus as shown at the right hand side of Fig. 1 there is an impression cylinder 1^a coacting with which is a plate cylinder 3^a. Above these are an impression cylinder 1^b and coacting plate cylinder 4^a; above which are an impression cylinder 1^c and coacting plate cylinder 5^a. 5 Similarly at the opposite or left hand end of the press are a lower impression cylinder 1^d coacting with a plate cylinder 2^a; above these an impression cylinder 1^e and coacting plate cylinder 7^a; and above these an impression cylinder 1^f and coacting plate cylinder 6^a. 10

Each of the plate cylinders 2^a, 3^a, 4^a, 5^a, 6^a, 7^a is preferably adapted to carry single page tubular plates; but the related coacting impression cylinders are preferably larger in diameter, or of the usual size, as above stated. The plate cylinders might be made to carry semi-cylindric page plates instead of the tubular page plates. 15

25 Preferably the plate cylinders 2^a, 3^a, 5^a, 6^a are parallel with and in web alinement with their respective related plate cylinders 2, 3, 5, 6; and the plate cylinders 4^a, 7^a are in web alinement with their respective related plate cylinders 4 and 7. Therefore, the cylinders 4^a and 7^a are arranged parallel with cylinders 4 and 7, adjacent one side of the press, while the other plate cylinders 2, 3, 5, 6-are arranged adjacent the other side of the 30 press. Each of the plate cylinders 2^a, 3^a, 4^a, 5^a, 6^a, 7^a is provided with a suitable inking mechanism (as indicated at i², i³, i⁴, i⁵, i⁶, i⁷) which supplies ink thereto, and is of well known construction and will be readily 35 understood by pressmen.

The press is provided with suitable guides for directing the several webs and portions of webs from the web supply rolls W, W', W², through the press, as hereinafter explained. Above each printing mechanism at the right hand side of the press is an angle bar, hereinafter referred to, whereby the printed web may be directed out of the press; and below each printing mechanism 45 at the left hand side of the press is an angle bar whereby the printed webs may be directed out of the press, as hereinafter described. Also above the left hand set of printing mechanisms, may be an angle bar 50 or bars and guide rollers, hereinafter described, which may be used when printing in multi-color.

When printing to full capacity in one color the press can be threaded as indicated 60 in Fig. 1. As shown therein the web coming from the roll W at the right hand end of the press is directed over a roller a, where it is preferably cut by a slitter S; one-half of the split web is then led over guide 65 rollers a', a², a³, a⁴, to and between the plate

cylinder 3 and impression cylinder 1; and printed on one side; said web is then carried past guide rollers a⁵, a⁶, a⁷, to and between the impression cylinder 1^a and plate cylinder 3^a, and then over guide rollers a⁸, a⁹, to an angle bar A over which it is turned and directed outside of the press to a second angle bar 8, or 8^a, over which it can be turned and directed over suitable guide rollers a¹⁰, a¹¹, a¹², a¹³, to a roller D above 75 the tops of the folders 9, or 9^a, of the usual construction, see Fig. 2, whereby the web can be folded. The other half of the web W after being split at roller a may be led down under rollers b, deflected over angle bars 2^y, 2^z (below and arranged like guides A', A² Fig. 2) and then led past guides b', b², to and between impression cylinder 1 and plate cylinder 2; thence to and between impression cylinder 1^d and plate cylinder 2^a and thence over roller b⁴ to an angle bar B and deflected to the side of the machine, and can be turned over angle bar 11, or 11^a; and then directed over suitable guides b⁶, b⁷ to 80 the roller D, and thence into the folder 9, 90 or 9^a.

The web from roll W' may be led over a guide c where it is split by splitter S'. One-half of this web then passes over guides c', c², c³, c⁴, to and between plate cylinder 4 and impression cylinder 1; thence the web is led over guides c⁵, c⁶ to and between impression cylinder 1^b and plate cylinder 4^a; thence over guides c⁷, c⁸ to angle bar A' by which it is directed out of the machine to an angle bar 8^b, or 8^c, (lying above the angle bars 8, 8^a and parallel therewith), and thence passes over rollers c⁹, c¹⁰, c¹¹, c¹² to roller D, and to either folder 9, or 9^a. 95

The other half of the web from roll W', passes from roller c' up over guides d past guides d', d², and between impression cylinder 1 and plate cylinder 5; thence over guides d³, d⁴, to and between impression cylinder 1^c and plate cylinder 5^a; thence over guides d⁵, d⁶, to angle bar A², by which the web is directed to one side of the machine to an angle bar 8^e, or 8^f, (parallel with the angle bars 8, 8^a) and thence the web is passed over guide rollers d⁷, d⁸, d⁹, to the 100 roller D, and into the folder 9, or 9^a. 115

The web from the roll W² at the other end of the machine passes over a roller e, where it is split by splitter S²; and one-half of this web passes over guides e', e², e³, to and between the plate cylinder 7 and impression cylinder 1; and thence over guide e⁴ to and between impression cylinder 1^e and plate cylinder 7^a; thence over guide e⁵ to an angle bar B' by which it is directed 120 out of the machine to an angle bar 11^b, or 11^c, (above angle bars 11 and 11^a), by which it is again deflected, and thence the web passes over guides e⁶, e⁷ to the roller D, 125 into the folder 9, or 9^a. 130

The other half of the web W^2 passes from roller e' to and past guides f, f', f^2 , to and between the impression cylinder 1 and plate cylinder 6; thence past guides f^3, f^4 , to and between the plate cylinder 6^a and impression cylinder 1^f ; thence over guide f^5 to an angle bar B^2 by which it is directed out of the machine to an angle bar 11^a , or 11^e , (parallel with angle bars 11 and 11^a), by which 5 the web is directed toward the folder, and it passes over guides f^6, f^7 , to the roller D and into folder 9, or 9^a .

It will be seen by reference to the drawing that each web or part of web is perfected 15 in its passage through the machine; one side of such web being printed by a printing couple adjacent the web roll, and the other side of such web being printed by the central impression cylinder and one of its related plate cylinders.

By reason of the laterally displaced arrangement of the plate cylinders I am able to use a four page wide web in the roll and to print each half of such web as it 25 passes through the machine by a two page wide plate cylinder. Each half of the web after printing is given a quarter turn and directed endwise of the plate cylinders out of the machine to one side of the press, 30 where it is preferably given another quarter turn over suitable angle bars and directed toward a folder at one side of the press, the folding rolls of such folder lying at right angles to the plate and impression cylinders.

35 I herein use the term "side of the press" with reference to the greater length of the press; taking the greatest length of the press as its longest diameter, and for convenience considering the web rolls as being 40 located at the ends of such press.

Assuming, for the purpose of description, that each plate cylinder is but two pages long and each web roll is four pages long, it will be seen that with the press 45 illustrated in the drawings I am able to print three four page wide webs simultaneously; and can assemble all the printed webs, at either folder 9 or 9^a ; or can assemble any desired number of webs or portions 50 of webs at either folder. The press shown can print two similar sized papers simultaneously; or can print two different sized papers simultaneously, up to the full page capacity of the press.

55 *Multi-color.*

The press threaded as shown in Fig. 1 is adapted to print and perfect the three webs only in one color. The press can be readily 60 threaded so as to print one or more webs in colors, as will be obvious to pressmen; merely as an example I have shown in Fig. 3 how one two page wide web could be printed in four colors on each side in the 65 press shown. In such case a two page wide

web W^2 may be led over roller e' up past guides g, g' and then between plate cylinder 6^a and impression cylinder 1^d receiving a first impression; then down to guide g^2 , thence past guide e^2 , thence between impression cylinder 2^a and plate cylinder 1^d to receive a second impression on the same side in color; then over guide g^3 to and over guide a^7 and between impression cylinder 1^a and plate cylinder 3^a receiving a third 75 color on the same side; then past guides a^8, a^9 to and between impression cylinder 1^c and plate cylinder 5^a ; receiving a fourth impression in color all on one side; and then the web is led past guide d^5 over guide d' , 80 to guide d^2 , then around the impression cylinder 1 successively past the plate cylinders 5, 3, 2 and 6, at each of which it may receive a perfecting impression in color; and then it passes over guides f^3, f^4 to guide 85 g^4 , thence over an angle bar B^3 , out of the press toward and over an angle bar 11^f (or 11^e) and is thereby deflected toward the folders and thence it is led over guide g^5 and under guide a^{12} to the roller D into 90 folder 9, or 9^a . With this arrangement it will be seen that a two page wide web can be perfected, if desired, in black and three colors during one passage through the machine. It will be obvious to pressmen that 95 additional webs might be printed and perfected in a less number of colors if desired; but it is unnecessary to attempt to explain herein all the possible methods of threading the press for multi-color work.

The capacity of the press could be varied within the scope of the invention by increasing or diminishing the number of plate cylinders coöoperating with cylinder 1; and correspondingly increasing or diminishing the 100 number of printing couples at the ends of the press. A press of half the capacity described could be built by entirely omitting the plate cylinders and printing mechanisms at either side of cylinder 1 which would 105 practically be to cut the press in half. The number of folders employed would of course depend upon whether it is desired to produce one or more papers simultaneously. If it was desired to produce more than two 110 papers at one time, additional folders could be used, as will be readily understood by press builders. Of course the number of web guides and arrangement and number of angle bars used would depend upon the 115 capacity of the press and the number of folders employed.

The capacity of the press could also be increased if desired by increasing the length of the plate and impression cylinders so 125 that each plate cylinder could carry three or more plates instead of two. While it is convenient to employ four page wide webs, two separate narrow webs could be employed if desired instead of one wide web; 130

but as a matter of convenience in handling the web rolls it is preferable to employ wide webs.

5 In Fig. 2 I have indicated another angle bar B^x parallel with angle bar B^y which will enable a web to be printed in multi-color, or by cylinders 4—4^a—7 and 7^a, and directed over angle bars 11^b or 11^c to the folders.

What I claim is:

10 1. In a rotary printing press, the combination of an impression cylinder, a plurality of laterally displaced plate cylinders coacting therewith adjacent opposite ends thereof, a plurality of printing couples arranged at opposite sides of the said cylinder, and means for directing webs through the individual printing couples and between the impression cylinder and the related coacting plate cylinders.

20 2. In a rotary printing press, the combination of a centrally disposed impression cylinder, a plurality of laterally displaced plate cylinders coacting therewith adjacent opposite ends thereof, a plurality of printing couples arranged at opposite sides of the said cylinder, means for directing webs through individual printing couples and between the impression cylinder and the coacting related plate cylinders to perfect the webs.

30 3. In a rotary printing press, the combination of an impression cylinder, a plurality of shorter laterally displaced plate cylinders coacting therewith adjacent opposite ends thereof; a plurality of printing couples arranged at opposite sides of the said cylinders; means for directing webs through the printing couples and between the impression cylinder and the related coacting plate cylinders, and folding mechanism adjacent the printing mechanisms to which the printed webs are directed.

40 4. In a rotary printing press, the combination of an impression cylinder, a plurality of laterally displaced plate cylinders coacting therewith, a plurality of printing couples arranged at opposite sides of the said cylinders, means for directing webs through the printing couples and between the impression cylinder and the related coacting plate cylinders; folding mechanism adjacent the printing mechanisms, and angle bars whereby the webs after being perfected may be turned at right angles and directed to the folding mechanism.

50 5. In a rotary printing press, the combination of an impression cylinder and a plurality of plate cylinders coacting therewith, the plate cylinders being shorter than the impression cylinder and located adjacent opposite ends thereof; with a plurality of printing couples arranged at opposite sides of said cylinders, the plate cylinders in said printing couples being located parallel with the related plate cylinders coacting with said

impression cylinder, so that webs printed by the printing couples may be led to the related plate cylinder coacting with said impression cylinder.

6. In a rotary printing press, the combination of an impression cylinder and a plurality of plate cylinders coacting therewith, the plate cylinders being shorter than the impression cylinder and located adjacent opposite ends thereof; a plurality of printing couples at opposite sides of said cylinders, the plate cylinders in said printing couples being located parallel with the related plate cylinders coacting with said impression cylinder so that webs printed by the printing couples may be led direct to the related plate cylinder coacting with the impression cylinders, folding mechanisms beside the printing mechanisms, and a plurality of oppositely disposed angle bars whereby the webs after being perfected may be turned and directed outside the machine, and again turned and directed to the folding mechanisms.

7. In a rotary printing press, the combination of an impression cylinder and a plurality of plate cylinders coacting therewith; with a plurality of superposed printing couples at one side of said cylinders, adjacent superposed printing couples being relatively laterally displaced.

8. In a rotary printing press, the combination of an impression cylinder and a plurality of plate cylinders coacting therewith; a plurality of superposed printing couples at opposite sides of said cylinders, adjacent superposed printing couples being relatively laterally displaced, and means for directing webs printed by the said printing couples to the related plate cylinders coacting with the said impression cylinder.

9. In a rotary printing press, the combination of an impression cylinder and a plurality of plate cylinders coacting therewith; a plurality of superposed printing couples at one side of said cylinders; adjacent superposed printing couples being relatively laterally displaced; with folding mechanism adjacent the printing mechanisms, and angle bars whereby the webs after being perfected may be turned and directed to the folding mechanism.

10. In a rotary printing press, the combination of an impression cylinder and a plurality of plate cylinders coacting therewith; a plurality of superposed printing couples at opposite sides of said cylinders, adjacent superposed printing couples being relatively laterally displaced, so that webs printed by the said printing couples may be led direct to the related plate cylinder coacting with the large impression cylinder; with folding mechanism adjacent the printing mechanisms, and angle bars whereby the webs after being perfected may be turned

at right angles and directed to the folding mechanism.

11. In a rotary printing press, the combination of an impression cylinder and a plurality of plate cylinders coacting therewith, the plate cylinders being shorter than the impression cylinder and located adjacent opposite ends thereof; with a plurality of superposed printing couples at one side 70
10 of said cylinders, adjacent superposed printing couples being relatively laterally displaced so that webs printed by the said printing couples may be led direct to the related plate cylinder co-acting with said impression cylinder.

12. In a rotary printing press the combination of an impression cylinder and a plurality of plate cylinders coacting therewith, the plate cylinders being shorter than the impression cylinder and located adjacent opposite ends thereof; a plurality of superposed printing couples at opposite sides of said cylinders, adjacent superposed printing couples being relatively laterally displaced, 75
20 and means for directing webs printed by the said printing couples to the related plate cylinders coacting with the said impression cylinder.

13. In a rotary printing press, the combination of an impression cylinder and a plurality of plate cylinders coacting therewith, the plate cylinders being shorter than the impression cylinder and located adjacent opposite ends thereof; a plurality of superposed printing couples at one side of 80
30 said cylinders; adjacent superposed printing couples being relatively laterally displaced; with folding mechanism adjacent the printing mechanisms, and angle bars 85
35 whereby the webs after being perfected may be turned and directed to the folding mechanism.

14. In a rotary printing press, the combination of an impression cylinder and a plurality of plate cylinders coacting therewith, the plate cylinders being shorter than the impression cylinder and located adjacent opposite ends thereof; a plurality of superposed printing couples at opposite 90
40 sides of said cylinders, adjacent superposed printing couples being relatively laterally displaced, so that webs printed by the said printing couples may be led direct to the related plate cylinder coacting with the 95
45 large impression cylinder; with folding mechanism adjacent the printing mechanisms, and angle bars whereby the webs after being perfected may be turned at right angles and directed to the folding mechanism.

15. In a rotary printing press, the combination of an impression cylinder and a plurality of plate cylinders coacting therewith; the plate cylinders being shorter than 100
50 the impression cylinder and located adjacent

opposite ends thereof; a plurality of superposed printing couples at one side of said cylinders, adjacent superposed printing couples being relatively laterally displaced according to the related plate cylinders co-acting with the impression cylinder; so that webs printed by the said printing couples may be led to the related plate cylinder coacting with said impression cylinder; folding mechanism at one side of the printing mechanisms, and means for directing printed webs from the printing mechanisms to the folding mechanism.

16. In a rotary printing press, the combination of an impression cylinder and a plurality of plate cylinders coacting therewith, the plate cylinders being shorter than the impression cylinder and located adjacent opposite ends thereof; a plurality of superposed printing couples at opposite 80
70 sides of said cylinders; adjacent superposed printing couples being relatively laterally displaced according to the related plate cylinders coacting with said impression cylinder, so that webs printed by the said printing couples may be led to the related plate cylinder coacting with said impression cylinder; with a plurality of folding mechanisms at one side of the printing mechanisms, and a plurality of angle bars whereby the webs after being perfected may be turned at right angles and directed to any folding mechanism.

17. In a rotary printing press, the combination of an impression cylinder, a plurality of laterally displaced plate cylinders co-acting therewith; a plurality of laterally displaced printing couples parallel with and adjacent said impression cylinder, and means for directing webs through the laterally displaced printing couples and then between the impression cylinder and the related co-acting plate cylinders.

18. In a rotary press, the combination of an impression cylinder, a plurality of shorter laterally displaced plate cylinders co-acting therewith; a plurality of laterally displaced printing couples at one side of said cylinder; and means for directing webs through the laterally displaced printing couples and then between the impression cylinder and the related co-acting plate cylinders.

19. In a rotary press, the combination of an impression cylinder, a plurality of shorter laterally displaced plate cylinders co-acting therewith; a plurality of laterally displaced printing couples adjacent one side of said cylinder, means for directing webs through the laterally displaced printing couples and between the impression cylinder 120
105 and the related co-acting plate cylinders, and a folding mechanism adjacent the printing mechanisms.

20. In a rotary press, the combination of an impression cylinder, a plurality of later- 130
110

ally displaced plate cylinders co-acting therewith; a plurality of laterally displaced printing couples adjacent the side of said cylinders, means for directing webs through 5 the laterally displaced printing couples and between the impression cylinder and the related coacting plate cylinders, a folding mechanism beside the printing mechanism, and angle bars whereby the webs after being perfected may be directed to the folding mechanism.

21. In a rotary printing press, the combination of an impression cylinder and a plurality of plate cylinders co-acting therewith, the plate cylinders being shorter than the impression cylinder and located adjacent opposite ends thereof; with a plurality of laterally displaced printing couples at one side of said cylinders, the said printing couples being located parallel with the related plate cylinders co-acting with said impression cylinder so that webs may be led from the laterally displaced printing couple to the related plate cylinder co-acting with 20 said impression cylinder.

22. In a rotary printing press, the combination of an impression cylinder and a plurality of plate cylinders co-acting therewith, the plate cylinders being shorter than the impression cylinder and located adjacent opposite ends thereof; with a plurality of laterally displaced printing couples at 30

one side of said cylinders, the plate cylinders in said printing couples being located parallel with the related plate cylinders co-acting with said impression cylinder so that webs may be led from the laterally displaced printing couple to the related plate cylinder co-acting with the said impression cylinder, a folding mechanism adjacent the printing mechanisms, and angle bars whereby the webs after being perfected may be turned and directed to the folding mechanism.

23. In a rotary printing press, the combination of an impression cylinder and a plurality of plate cylinders co-acting therewith, the plate cylinders being shorter than the impression cylinder and located adjacent opposite ends thereof; with a plurality of laterally displaced printing couples at one side of said cylinders the plate cylinders in said printing couples being located parallel with the related plate cylinders co-acting with the said impression cylinder so that webs may be led from the laterally displaced printing couples to the related plate cylinders co-acting with the large impression cylinder; folding mechanism, and means whereby the webs after being perfected may 60 be directed to the folding mechanism.

In testimony that I claim the foregoing as my own, I affix my signature.

HENRY F. BECHMAN.
